UNITED STATES PATENT OFFICE.

JACK C. JANKUS, OF SCRANTON, PENNSYLVANIA, ASSIGNOR TO WOMAN'S INSTITUTE OF DOMESTIC ARTS & SCIENCES, INC., OF SCRANTON, PENNSYLVANIA, A CORPORATION OF DELAWARE.

PULP MOLD.

Application filed June 26, 1920. Serial No. 391,873.

To all whom it may concern:

Be it known that I, JACK C. JANKUS, a citizen of the United States, residing at Scranton, in the county of Lackawanna and 5 State of Pennsylvania, have invented new and useful Improvements in Pulp Molds, of which the following is a specification.

This invention relates to molds or presses for plastic materials and more particularly 10 to presses for making dress forms from paper pulp and similar substances. My improved mold is especially adapted for forming the sections of dress forms such as are illustrated in my concurrently filed application, Serial No. 392,124, dated June 26, 15 1920.

Heretofore in the formation of the articles referred to great difficulty has been experienced in effecting quantity production 20 of the forms, certain methods now in use involving the tedious and laborious building up by hand of the articles in question.

The objects of the present invention are to provide an apparatus for molding and 25 pressing dress forms in sections in such manner that the forms may be readily and easily assembled, to provide a quick pressing and drying mold for these articles which shall be relatively simple of construction, 30 economical in operation and consist of few parts and which shall reduce the cost of manufacture of dress forms to a considerable extent.

I have illustrated one embodiment of my 35 invention in the accompanying drawings, wherein:

Figure 1 is a sectional elevation of a press constructed according to my invention.

Figure 2 is a side elevation partly in section of a portion of a press constructed according to the invention.

Figure 3 is a longitudinal vertical section through the base portion of a press adapted to mold the upper back portion.

45 Figure 3^a is a perspective of one of the mold members used in the press illustrated in Figure 3.

Figure 4 is a sectional elevation showing the lower back spider.

50 Figure 4^a is a perspective of the mold member used in Figure 4.

Figure 5 is a transverse sectional view of the lower front spider.

Figure 5^a is a perspective of the mold member used in Figure 5. 55

Figure 6 is a top plan view of the upper front spider.

Figure 7 is a side elevation of the spider illustrated in Figure 6.

Figure 7^a is a perspective of the upper 60 front mold member.

Figure 8 is a perspective vertical section through a portion of my improved press.

Figure 9 is a fragmentary section of a modified form of upper front mold member. 65

Figure 9^a is a perspective view of a modified form of upper front mold member.

Referring to the drawings, wherein similar numerals denote like parts throughout the several views, my improved apparatus 70 comprises a base 1 which is preferably formed with a hollow interior and is adapted to be heated by steam. The upper face of this base section is formed with a suitably shaped recess, as at 2, generally designed to simulate a portion of the human 75 form, whereby it is adapted to seat the mold members of the apparatus.

In order to facilitate the feeding of material to the press the neck portion 3 of the 80 base member is formed with an inlet opening 4 controlled by a suitable plunger valve 5 and in communication with a conduit 6 leading from a supply tank (not shown) adapted to contain the plastic material to be 85 pressed.

The mold members of the apparatus include female molds 7 which assume the different forms required to shape the several sections of the dress form. These female 90 mold members are preferably constructed of metal and have a plurality of perforations therethrough, whereby heat from the base is freely transmitted to the material under pressure and excess water in such material 95 permitted to drain off. I also provide a plurality of male mold members 8 which are likewise formed of sheet metal and of contours to fit within the respective female mold members. These male mold members 100 are perforated, as indicated at 8^a. In the modified form of female mold member illustrated in Figure 9^a for forming the upper front portion of the dress form, I have shown the mold as formed with a centrally 105 positioned longitudinal embossment 7^a. This

is provided in order to produce a center-line body groove in the molded material. The male mold members 8 are provided with side flanges 9 whereby the article molded 5 may be formed with projecting side flanges. For use in connection with the male mold members, I provide a backing or spacing plate 10. This plate is formed, preferably, of sheet metal and has a plurality of apertures 11 therethrough, the edges of the apertures being burred outwardly, as indicated at 12, whereby spacing members are provided which maintain the backing plate spaced apart from the male mold member. 10 Such construction is preferred in order that there may be a free channel for the drainage of the excess water exuding from the pressure applying mold member during the pressing operation. A plurality of frames 15 or spiders 13 are mounted within the spacing plate, these spiders each being formed with a plurality of transverse ribs 14 and a pair of upwardly extending arms 15. The spiders are further each provided with a 20 seating as at 16 for a vertically disposed pressure shaft 17.

It will be understood that in order to secure the best results, the spiders assume various shapes, depending upon the mold members with which they are used. For example, in Figure 3 of the drawings, I have illustrated the form of spider best adapted to cooperate with the upper back-forming mold plate, Fig. 4 the lower back-forming, 30 Fig. 5 the lower front-forming, Figs. 6 and 7 the upper front-forming types, for forming the various parts of the upper and lower sections of the dress form described in my co-pending application above referred to. 35 In order to provide for the ready draining of water or excess liquid from the press the base is formed with a plurality of drainage apertures as 18 communicating with the lower front portion of its recessed top and 40 extending to the front of the base.

The operating mechanism for my press comprises a cylinder 19 housing a piston 20 connected at one end to the vertical shaft 17. The piston is actuated downwardly through 45 means of compressed air or steam admitted through a conduit or pipe 21 and in an upward direction through means of a conduit or pipe 22. The admission of the actuating fluid is controlled from the common supply pipe through means of a usual three-way valve, such as is indicated by 23.

The pressure cylinder may be supported by any suitable means. In Figure 1 of the drawings I have illustrated a form which I 50 consider preferable at this time and which includes the end plate 24 formed with a central aperture for the passage of the piston, which apertures formed with a packing gland 25. The end plate is also formed with 55 an inlet connection 26 for pipe 22. The end

plate 24 is bolted to and supported by the side standards 27 which are formed with vertically grooved slideways 28 for the arms 15 of the spider. These side standards are secured by any suitable means, such as by 70 bolts 29 to the base of the press. In order to maintain pressure on the material without waste of steam pressure, I pivot catch levers 30 to two of the side standards. These levers are adapted to cooperate with the upper end 75 of the side arms of the spider to maintain the spider and associated mold members in pressing position so long as may be desired. Stop pins 31 are secured to the base 1 and project slightly above the upper slanting 80 surface 32 of the latter into the path of the shoulders 33 formed on the arms 15, in order to limit the downward motion of the male die so as to establish the required thickness of the molded product. 85

In the operation of my device one of the lower or female mold members is placed in position on the base, the upper mold or male member and its associated parts are moved through means of the pressure organization 90 to a position adjacent the lower mold member, whereupon, the plastic material is admitted to the lower mold. When a sufficient quantity of material has been placed in the mold, the plunger is further actuated, whereupon, the article will be pressed to the desired form, the steam heated base operating to thoroughly dry the article within a short period of time and the excess moisture pressed from the article during the operation being drained off through outlet 18 in the base member. 95

I claim:—

1. In a press for shaping plastic material, the combination of pressure applying mechanism, movable and stationary mold members associated with said mechanism, means for feeding plastic material to the mold members, means for applying pressure to the movable mold member, and devices for locking said movable mold member in position for exerting the desired maximum compression on the plastic material. 105

2. In a press for plastic material, a portion formed with a recessed top simulating a portion of the human form, a substantially horizontal aperture in one end of said base constituting an inlet for plastic material, a valve controlling the passage of material through said aperture, a mold member adapted to be positioned in said recessed base to receive the plastic material, a movable mold member adapted to cooperate with said first-named mold member to form the plastic material, and means for applying pressure to said movable mold member. 115

3. In a press for shaping plastic material, a base portion formed with a recessed top simulating a portion of the human form, an inlet opening for plastic material in said 120 125 130

base, a mold member shaped to fit within said recessed base and adapted to receive the plastic material to be pressed, a second mold member shaped to simulate a portion 5 of the human form and adapted to fit within said first-named mold member to shape the material contained therein, elastic fluid means for applying pressure to said second-named mold member, and means independent 10 of said elastic fluid system for locking said second-named mold member in pressing position whereby pressure of the elastic fluid may be relieved.

4. In a pulp press, a lower mold member 15 of perforated sheet metal shaped to simulate a portion of the human form and adapted to receive material to be pressed, means for supporting said lower mold member, means for supplying material to be pressed to said 20 lower mold member, an upper mold member of contour to fit within said lower mold member and having a plurality of perforations therethrough, a spacing plate mounted in said upper mold member, means for 25 maintaining said spacing plate and upper mold member in spaced relation, a spider superimposed on said spacing plate, and means connected to said spider for actuating said upper mold member to apply pressure 30 to the material in said lower mold member.

5. In a pulp press, a steam heated base portion, an inlet opening and controlling valve positioned in the neck of said base portion, a lower mold member mounted in 35 said base portion, an upper mold member adapted to cooperate with said lower mold member, said upper mold member being

formed with a series of perforations therethrough, a spacing plate having a plurality of burred openings therethrough positioned 40 in said upper mold member, a spider affixed to said spacing plate, and means acting upon said spider to press said upper mold member within said lower mold member.

6. In a press for shaping plastic material, 45 a mold member shaped to simulate a portion of the human form, said mold member being formed on its inner side with a centrally positioned longitudinal embossment adapted to form a groove in the finished product, a 50 second mold member shaped to fit within said first-named mold member, means for supporting said mold members, and means for applying pressure to said second-named mold member. 55

7. In a press for shaping plastic material, the combination of a fixed mold member shaped to simulate a portion of the human form, a movable mold member shaped to fit within said first-named mold member, 60 mechanism for actuating said movable mold member for compressing the plastic material within the mold, means to limit said movement to establish the required thickness of the molded products and a device for locking the mold members in the position determined by said means. 65

In testimony whereof I have hereunto set my hand in presence of two subscribing witnesses.

JACK C. JANKUS.
